ADJUSTABLE BOX SPRINGS

Abraham Bloom, 721 Arlington Ave., Plainfield, N.J.

Filed Apr. 24, 1958, Ser. No. 730,614

1 Claim. (Cl. 5—248)

2

decreases thus the firmness of the box spring 1 may be varied as desired.

The drawings and above description refer to a double size box spring with each side adjustable. It may be in some cases preferred to have only one side adjustable, or in the case of a single size or twin size box spring, the adjusting mechanism consisting of posts 8, members 9 and 10, longitudinal bars 11, 12 and 13 and other associated parts would be located at the center and parallel to the sides of the box spring. Also whereas the drawings indicate that bars 11, 12 and 13 are of wood, it is obvious that these members may also be made of metal. The invention is subject to modifications coming within the scope of the claim.

15 I claim:

In a box-spring structure for beds and the like, the combination comprising a normally stationary and rigid underframe structure adapted to support a flexible bed spring-unit, said spring-unit consisting of a flexible upper grid section defining the upper plane and surface area of the spring-unit and a flexible under grid section of substantially equal area and a plurality of coiled spring elements arranged on vertical axes between said flexible upper and under grid sections, means for securing said spring-unit to said rigid underframe including a plurality of tie cords connected at their upper ends to the said flexible upper grid section of the spring-unit and at their lower ends to said rigid underframe structure, and a plurality of independently operable screw means 20 threadably engaged with said rigid underframe structure and operative against the under surface of the flexible under grid section of the spring unit adapted when selectively actuated to flex the said under grid section at localized areas whereby to vary the firmness of the 25 spring unit at localized zones, said tie-cords connecting the upper flexible grid section of the spring unit to the rigid underframe structure functioning to restrain the upper grid section from bulging when said screw means are 30 threadably engaged with the under surface of the flexible under grid section of the spring unit adapted when selectively actuated to flex the said flexible under grid section at localized areas whereby to vary the firmness of the 35 spring unit at localized zones, said tie-cords connecting the upper flexible grid section of the spring unit to the rigid underframe structure functioning to restrain the upper grid section from bulging when said screw means are 40 actuated to flex the said flexible under grid section of the spring unit.
